UNITED STATES PATENT OFFICE.

JAMES WALLACE, OF OBENHEIM, ALSACE, GERMANY.

COAT-HANGER.

1,059,649.

Specification of Letters Patent.

Patented Apr. 22, 1913.

Application filed May 6, 1912. Serial No. 695,369.

To all whom it may concern:

Be it known that I, JAMES WALLACE, subject of the King of Great Britain and Ireland, residing at Obenheim, Alsace, in the State of Alsace-Lorraine, Germany, have invented certain new and useful Improvements in and Relating to Coat-Hangers, of which the following is a specification.

My invention relates to an improved coat hanger or shoulder piece made in two halves hinged together so as to fold one over the other.

In accordance with my invention I employ two members or frames of wood or other suitable material, hinged together end to end so as to open out flat or fold one against the other. Hooks or catches on one frame are provided to engage eyes on the other so as to maintain them in the open position when in use, and a catch is also provided to hold the two frames together when folded.

The coat hanger or shoulder piece is suspended by a device which is held in a recess formed between the two members when they are opened. Preferably this device is a loop formed of wire and having the two lower ends turned out to engage in sockets in the ends of the two frames, between which it is clamped. A suitably shaped recess is formed in one or both of the frames, so as to afford a pocket between the members when folded, for this suspending loop to lie in.

The lower member of one or both of the frames carries a hat or coat brush, either let into the lower member or otherwise suitably attached thereto.

A method of carrying out my invention is shown in the accompanying drawings in which:—

Figures 1 and 2 are respectively elevation and plan of my improved coat hanger in the open position; and Figs. 3 and 4 are respectively cross section and elevation of the coat hanger in the closed position.

The two frames A having the upper curved members a and lower straight members a^1 are hinged together at a^2 and hooks 50 or catches B on one frame engage eyes b on the other to maintain the coat hanger in

the open position. The suspending loop C has turned out ends c to engage in sockets a^3 in the ends of the frames, between which it is held when they butt together in the open 55 position. A hat or coat brush D is shown attached to the straight member a^1 of one of the frames A and a catch a^4 is provided to engage a screw or pin a^5 to hold the frames together when closed.

Figs. 3 and 4 show the coat hanger folded with the suspending loop C between the frames in recesses a^6 in one of the frames.

What I claim as my invention and desire to secure by Letters Patents is:—

1. In a coat hanger, the combination of two members hinged so as to fold one against the other and having a recess formed between their abutting ends when opened, one or both of said members also having a recess in its side so as to afford a pocket when the members are folded together; and a removable hanging device which when the members are opened is adapted to be held in the recess between their abutting ends and 75 when the members are closed is adapted to be received in the pocket formed between them.

2. In a coat hanger, the combination of two members hinged so as to fold one against 80 the other, one or both of said members having a recess in its sides so as to afford a pocket when the members are folded together, and a removable hanging device adapted to be received in said pocket between the members when the said members are folded.

3. In a coat hanger, the combination of two members, a hinge connecting the same, said members having sockets in their abutting ends, a wire hanging loop having a lower portion with out-turned ends received in said sockets and clamped between said members when the latter are opened into alinement, and means for holding said members in such open condition.

In witness whereof I have hereunto set my hand in the presence of two witnesses.

JAMES WALLACE.
